US00D621049S

(12) **United States Design Patent**
Takano et al.

(10) **Patent No.:** US D621,049 S
(45) **Date of Patent:** ** Aug. 3, 2010

(54) **GLUCOSE METER**

(75) Inventors: **Hiroshi Takano**, Ehime (JP); **Noriyuki Shinohara**, Ehime (JP); **Carol Reno**, Essex Fells, NJ (US); **Art Oliveira**, Rockaway, NJ (US); **Gerald Shaffer**, Elkhart, IN (US); **Raymond Yao**, Tarrytown, NY (US)

(73) Assignees: **Panasonic Corporation**, Kadoma-shi (JP); **Bayer Healthcare LLC**, Tarrytown, NY (US)

(**) Term: **14 Years**

(21) Appl. No.: **29/320,460**

(22) Filed: **Jun. 27, 2008**

(30) **Foreign Application Priority Data**

Dec. 27, 2007 (JP) 2007-035850

(51) **LOC (9) Cl.** **24-01**

(52) **U.S. Cl.** **D24/169**

(58) **Field of Classification Search** D24/169, D24/186, 216, 223; D10/81; 600/309, 316, 600/322, 365, 368

See application file for complete search history.

OTHER PUBLICATIONS

Official Action (Enquiry) from the Patent Office of The Russian Federation dated Jul. 6, 2008, issued in corresponding Russian Application No. 2007502010, filed Jul. 6, 2007.

Primary Examiner—T. Chase Nelson

Assistant Examiner—Anhdao Doan

(74) *Attorney, Agent, or Firm*—Christensen O'Connor Johnson Kindness PLLC

(57) **CLAIM**

The ornamental design for a glucose meter, as shown and described.

DESCRIPTION

FIG. 1 is a perspective view of the front, right side and bottom of a glucose meter showing our new design;

FIG. 2 is a perspective view of the rear, left side and top thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.
